INVENTOR

BY *Victor J. Evans*

ATTORNEY

J. A. Wynn
WITNESS:

WITNESS:

UNITED STATES PATENT OFFICE.

CHARLES A. ALDERSON, OF VIRDEN, ILLINOIS.

WIRE STRETCHER.

Application filed December 31, 1926. Serial No. 158,284.

This invention relates to fence wire stretchers to stretch the fence vertically thereof.

Another object of the invention contemplated 5 plates means engageable with the upper and lower portions of the fence.

A further object of the invention comprehends means adapted for use in conjunction with the fence engaging means for sustaining 10 the latter in a desired position.

With the above and other objects in view, the invention further consists of the following novel features and details of construction, to be hereinafter more fully described, 15 illustrated in the accompanying drawings and pointed out in the appended claims.

In the drawing:

Figure 1 is an elevation of the invention as applied.

Figure 2 is a longitudinal sectional view thereof.

Figure 3 is a transverse section taken on line 3—3 of Figure 2.

Referring to the drawing in detail, where- 25 in like characters of reference denote corresponding parts, the reference character 10 indicates a length of fence wire disposed adjacent a post 11. It is generally known that cattle and other domestic animals often 30 crush fences where the latter sag when traversed. It is the cardinal purpose of the invention to provide means to stretch the fence wire vertically to remove the kinks therein caused by crushing.

35 In carrying out my invention I provide a standard 12 having an offset plate 13 disposed adjacent the lower end thereof. An elongated plate 14 providing offset end portions 15 carried upon one side of the stand- 40 ard 12 at right angles to that of the plate 13. Said plate 14 provides a plurality of spaced openings 16 adapted for registration with corresponding openings, not shown, in the standard 12. An operating lever 17 is 45 adapted for pivotal rocking movement between the inner side of the elongated plate 14 and the adjacent side of the standard 12 and upon a pivot pin 18 passed through register- 50 ing openings at a desired height in the plate 14 and standard 12. As illustrated in Figure 2 of the drawing, said operating lever 17 is pivoted off center.

A cross arm 19 carried upon the shorter end of the lever from the pivot pin there- 55 for has provided a plurality of upstanding headed studs 20 upon the upper surface

thereof. The upper and lower portions of the fence 10 are engageable by the plate 13 and the cross arm 19; the headed studs are adapted to prevent displacement of the wire 60 thereon. The height of the operating lever 17 upon the standard 12 is regulated by the placing of the pivot pin 18. When the operating lever 17 is depressed the cross arm 19 is moved upwardly whereby the wire will 65 be stretched and kinks removed. A pawl 21 is likewise pivotally mounted between the plate 14 and the adjacent side of the standard 12 by a pivot pin 22. The free end of said pawl is adapted for engagement with ratchet 70 teeth 23 upon the upper side edge of the operating lever 17 to lock the latter in a desired position, during the stretching of the fence wire, substantially as illustrated in Figure 2 of the drawing. 75

It will be noted from the foregoing description and accompanying drawing that the pawl 21 may follow the operating lever 17 to check the same at any desired position in the length of the plate 14 upon the stand- 80 ard 12 to accommodate the various widths and heights of running fence wires.

The invention is susceptible of various changes in its form, proportions and minor details of construction and the right is here- 85 in reserved to make such changes as properly fall within the scope of the appended claims.

Having thus described my invention, what is claimed is:

1. A fence wire stretcher comprising a 90 standard having an offset plate adjacent the lower end thereof, an elongated and apertured plate provided with offset end portions carried upon one side of the stand- 95 ard at right angles to that of the offset plate, an operating lever pivotally mounted off center at an appropriate point in the length of the standard and elongated plate and within the space defined therebetween, a cross arm carried upon one end of the operating lever 100 adapted to engage the upper portion of the wire and to stretch the latter from the offset plate, and a pawl detachably mounted upon the standard adapted to follow and lock the operating lever in a desired position during 105 the stretching of the wire.

2. A fence wire stretcher comprising a standard, an elongated and apertured plate being provided with offset ends secured upon one side of the standard, an operating lever 110 eccentrically fulcrumed between the standard and plate, a cross arm carried upon the

shorter end of the lever having headed studs upon the upper side thereof, and an offset plate carried adjacent the lower end of the standard adapted for use in conjunction with the cross arm for vertically stretching fence wire therebetween.

3. A fence wire stretcher comprising a standard, an elongated and apertured plate being provided with offset ends secured upon one side of the standard, an operating lever eccentrically fulcrumed between the standard and plate, a cross arm carried upon the

shorter end of the lever having headed studs upon the upper side thereof, an offset plate carried adjacent the lower end of the standard adapted for use in conjunction with the cross arm for vertically stretching fence wire therebetween, and a pawl pivotally mounted between the post and elongated plate adapted for engagement with the operating lever to hold the latter in a desired position while the wire is being secured upon a fence post.

In testimony whereof I affix my signature.

CHARLES A. ALDERSON.
